UNITED STATES PATENT OFFICE.

WILLIAM L. BLACKWELL, OF DAYTON, OHIO.

VEHICLE-HEATER.

249,306.

Specification of Letters Patent. Patented Dec. 11, 1917.

Application filed November 1, 1916. Serial No. 122,810.

To all whom it may concern:

Be it known that I, WILLIAM L. BLACKWELL, a citizen of the United States, residing at Dayton, in the county of Montgomery and State of Ohio, have invented certain new and useful Improvements in Vehicle-Heaters; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to a heater for automobiles. The object of the invention is to provide a heater having a special adaptation for automobile purposes and by means of which the heat of the exhaust products of combustion is utilized in a manner and by means to be hereinafter described more particularly in connection with the accompanying drawings.

In the accompanying drawings, Figure 1 is a side elevation of an inclosed automobile with a portion of the side broken away to disclose the location of my improved heater appliance; Fig. 2 is an enlarged perspective view of the heater with a part thereof shown in section; Fig. 3 is a longitudinal sectional view on the line 3—3 of Fig. 2; Fig. 4 is a transverse sectional view on the line 4—4 of Fig. 2; Fig. 5 is a perspective view illustrating an end of the heater, other portions being broken away; and Fig. 6 is a detail perspective view of an inner section of the heater.

In the following description, similar reference characters indicate corresponding parts in the drawings.

My improved heater is designed to be placed in a position below the floor of the vehicle and in a position to receive the exhaust from the engine of the automobile and to conduct it through a circuitous path through the heater where it heats a plurality of walls to which is subjected air from the outside atmosphere. This air is instantly heated and is discharged above the floor of the vehicle through a grid, all of which will be hereinafter more fully described. The heater lies crosswise below the floor of the vehicle and consists of an oblong rectangular metallic box 1 which is inclosed at each end by metallic end walls 2 which set in from the ends of said casing and are welded in such positions as are all other parts of the heater. The wall of the box 1 which faces the front of the vehicle is provided with a plurality of air openings 6 through 60 which the air enters as the vehicle advances. The walls of the outer box or casing terminate at their upper edges in double flanges 3 which lie outwardly. These flanges 3 of the heater may lay flush with the top of the floor 4 of the automobile and thus avoid any obstruction at that point. The said flanges 3 are formed by bending the margins of the walls of the outer box or casing over upon themselves. The flanges 3 when 70 so formed provide space for supporting the grid or top plate of the heater to be herein-after referred to. Within the casing 1 is a second casing or box 7 made from one piece of metal into a longitudinal, rectangular 75 form. The top 10 of this inner box has abutting flanges which are united as by welding, to form a central longitudinal rib 10'. This inner box 7 is of suitable dimensions to provide the proper air circulating 80 spaces 8 below, at the sides and thereabove. The said inner box 7 is maintained in this position by means of transverse ribs 8' which lie across the bottom of the outer casing and upon which the inner casing 85 rests. These ribs 8' are welded to the bottoms of both casings. The ends 7' of this inner box or casing are set in and are welded to the ends of said inner casing in a manner similar to the union of the ends of the outer 90 casing with the walls thereof. Within the inner casing or box 7 a rectangular shell is placed providing longitudinal walls 9 which terminate in outwardly lying flanges 9' by means of which this inner member is 95 welded to the top 10 of the inner casing or box 7. By means of this inner section a series of longitudinal heated channels or spaces 11 are provided which extend throughout the length of the heater and 100 communicate at the ends by means of openings 15 in the two inner walls 9, as shown in Fig. 3. The course of the heat within these heat channels or spaces is indicated by the several arrows. The bottom of the 105 heater at one end is provided with an opening 13 which receives the nipple of a valve 17 which is arranged at a point of the exhaust pipe 16 that leads from the engine of the vehicle (not shown) to the usual exhaust point of the vehicle. This exhaust pipe 16 is intercepted by the valve 17 which

may be operated to discharge the exhaust products of combustion into the heater by operating a common form of lever 19 within convenient reach of the foot of the driver 5 of the vehicle and which lever is connected to the valve in any suitable manner, for example, by a rod 20. The hot gases or products of combustion entering the opening 13 in the heater travel back and forth 10 throughout the length of the heater in the circuitous path indicated and discharge through an opening 14 in the bottom of the heater at the end opposite that having the inlet opening 13. The outlet or discharge 15 opening 14 communicates with a heater exhaust pipe 18 which may discharge the products of combustion into the usual exhaust outlet for explosive engines. The heated air discharges through a grid 5 which constitutes the top of the heater and lies above 20 the top horizontal air space therein. This grid or grid 5 is secured in such position by having its edges or margins 4 inclosed between the folds or flanges 3 of the outer 25 box or casing of the heater. When the heater is in position the grate 5 lies practically flush with the floor of the automobile or vehicle in which it is placed. The number of air openings 6 and the size thereof 30 depend somewhat upon the air or dimensions of the heater, it being necessary under all conditions to provide for the admission of sufficient air to heat the space within the body closure of the car. It will be understood 35 that when the car is moving forward the passage of the air into the heated spaces 8 is increased. It will be also understood that when it is desired to exclude the heat the products of combustion may be permitted 40 to pass through the valve 17 without entering the heater.

Having described my invention, I claim:

1. In a heating apparatus for automobiles, the combination with a vehicle and the 45 engine for driving the same and its exhaust pipe, of a heater mounted transversely below the floor of the vehicle and consisting of inner and outer casings which provide air space around the interior sides and bottom of the outer casing and a series of openings in the front wall of said outer casing communicating with the air space on one side of the heater, a series of walls on the

interior of the inner casing providing a series of longitudinal passages adapted to be heated by the products of combustion discharging from said engine, a grate or grid forming the top of the heater and communicating with the air spaces thereof and with the interior of the vehicle, a valve controlling the passage of the products of combustion discharging from the engine and directing the same to said heater, and an outlet from said heater for the discharge therefrom of said products of combustion after traversing the heat passages on the interior of the heater.

2. A heater of the character specified, comprising an outer rectangular casing having in the front wall thereof a series of air 70 openings, an inner rectangular casing around the outer sides and ends of which spaces are provided for the air entering said openings to circulate through, transverse ribs uniting the inner and outer casings and 75 maintaining said inner casing in a position to preserve said air spaces, said inner casing consisting of a shell the top of which is provided with a centrally-disposed upturned longitudinal rib, a rectangular shell 80 arranged within said inner casing and consisting of two longitudinal walls the upper margins of which terminate in outwardly-lying flanges which abut with the upper portions of the side walls of said inner casing, 85 said shell providing a central longitudinal heat space and side, parallel longitudinal heat spaces which extend throughout the length of the heater and communicate one with the other by means of openings in opposite ends of the walls of said inner shell, and a grate mounted over the air spaces formed by the inner and outer casings and supported between the margins of the outer casing and above the longitudinal top rib 90 of said inner casing, the outermost side heat spaces having openings which communicate respectively with heat inlet and exhaust pipes, substantially as specified.

In testimony whereof I affix my signature, 100 in presence of two witnesses.

WILLIAM L. BLACKWELL.
